CLAIM

The ornamental design for a tire pressure gauge, as shown and described.

DESCRIPTION

FIG. 1 is a front and top-right perspective view of a tire pressure gauge showing our new design;

FIG. 2 is a front elevational view thereof;

FIG. 3 is a right side elevational view thereof, the left

side view being a mirror image thereof;

FIG. 4 is a rear elevational view thereof;

FIG. 5 is a top plan view thereof;

FIG. 6 is a bottom plan view thereof.

FIG 1

FIG 2

FIG 3

FIG 4

FIG 5

FIG 6
